UNITED STATES PATENT OFFICE.

HENRY E. HALLBORG, OF WASHINGTON, DISTRICT OF COLUMBIA.

HIGH-SPEED SIGNALING SYSTEM.

Application filed September 1, 1923. Serial No. 660,637.

To all whom it may concern:

Be it known that I, HENRY E. HALLBORG, a citizen of the United States of America, and a resident of Washington, District of Columbia, have made new and useful Improvements in High-Speed Signaling Systems, of which the following is a specification.

My invention relates broadly to a system for closing electrical circuits, and more particularly to a method for controlling a radio transmission system at high speeds.

One of the objects of my invention is to provide an arrangement of electrical circuits for controlling the rapid closing and opening of contacts at a radio transmitting station which contacts may be connected to various parts of the radio transmitting circuits for controlling the transmission of telegraph signals at high speeds.

Another object of the invention is to provide a circuit arrangement having such characteristics that rapid de-energization of the magnet coils occurs within a negligible differential time period after the energy is cut off from the control circuits whereby keying of the radio signaling circuits may be obtained with negligible electrical inertia.

Another object of the invention is to provide a radio transmitting control circuit capable of operating at the radio transmitting station from a distant control point connected by line wire to the radio transmitting station, the electrical characteristics of the control circuits being such that positive and reliable operation for high speed signaling is obtained.

Other and further objects of my invention will be understood by consideration of the following specification and by reference to the accompanying drawings, in which:

Figure 1 is a schematic wiring diagram showing my control circuit applied to a high power uniwave arc signaling system; Fig. 2 is a wiring diagram showing the electrical connections between the distant control line and the sets of control keys which move the contacts that are connected with the arc transmitter circuits for transmitting or suppressing the high frequency signaling energy; Fig. 3 is an elementary plan view illustrating the arrangement of opening and closing coils in each of the keys which control the position of contacts connected with

the radio signaling circuits; Fig. 4 is a side elevation of the key construction shown in Fig. 3 illustrating the arrangement of the core stampings which carry independently the opening coils and the closing coils of the control system; Fig. 5 is an elementary diagram showing the principle involved in my invention; and Figs. 6 and 7 are fragmentary views showing the arrangement of the multiple keys used in shunting the different portions of an arc transmitting circuit.

Referring more particularly to the drawings, Fig. 1 shows an arc transmission circuit for signaling with a single wave with which my control system herein described has proven its effectiveness. It will be understood that I have selected this transmitting circuit merely for the purpose of illustrating one application of my invention and that the invention is capable of application to other forms of circuits.

Reference character 1 indicates the power circuit which supplies the direct current energy for the arc 2. The arc is provided with the arc field 3. A primary oscillating circuit is provided around the arc including capacity 4, inductance 5, primary coupling coil 6, and the antenna equivalent load resistance or absorbing resistance 14 which may be cut in or out of circuit of a series of keys represented more in detail in Fig. 6 and which for the purpose of illustrating the application of the invention has been represented by a single key 15 in Fig. 1. The primary coupling coil 6 is inductively coupled with secondary coupling coil 7 connected in the antenna ground circuit in series with antenna 8, loading coil 9, variometer 9, ammeter 10, and ground 11. The secondary coupling coil 7 has all or groups of its turns shunted by a series of keys 18, as shown more fully in Fig. 7 and which for the purpose of illustrating the invention has been indicated by a single key across the terminals of the secondary coupling coil 7 in Fig. 1. The keys 15 and 18 have their operating contacts 19-20 and 21-22 carried upon metallic arms 16 and 17. The arms are mounted for limited rotary movement on insulated axis members which are represented by broken lines 23 and 24. Laminated silicon steel armatures 25 and 26 are mounted to drive arms 16 and 17 about centers for closing or opening the contacts. Each key is provided with a plurality of

opening coils 27 also marked OC for the purpose of clearness and a plurality of closing coils 29 also indicated by letters CC throughout the drawings. The opening coils 27 are provided with terminals 28 and are diagonally oppositely positioned with respect to closing coils 29 having terminals 30, as will be seen more clearly in Figs. 3 and 4. The operating keys have their opening and closing coils formed on a laminated silicon steel stator, that portion of the stator 36 which carries the opening coils 27 being separated from that portion of the stator 37 which carries the closing coils 29 by means 15 of the magnetic barrier 38.

Each key consists of a double laminated steel bi-polar stator carrying one pair of closing coils 29 and one pair of opening coils 27. The opening and closing coils 27 and 29 control the position of the laminated steel armature 25 which carries the high tension contacts. The opening and closing magnetic circuits are independent to prevent magnetic reaction. The schematic connection of four such double acting keys is illustrated in the wiring diagram Fig. 5. The closing coils of keys 15 are connected in series with the opening coils of keys 18. The opening coils of keys 15 are connected in series with the closing coils of keys 18. The opening and closing keys 15 and 18 are controlled by front and back contacts 57 and 59 of a pilot key 31 which may also be a double acting magnetic key. Accelerating resistances 32 cause rapid deenergization of the magnet coils by improvement of the time constant $\frac{L}{R}$ of the magnets under short circuit by the contacts of key 31 by arm 58 connecting with contacts 57 and 59. The line resistances 33 provide the required $\frac{L}{R}$ ratio for the armature energizing coils as well as prevent possible short circuit of the line by mal-adjustment of the contacts of key 31. The contacts of key 31 are shunted by the condensers 34 and 35 to prevent sparking.

As will be seen in Figs. 1 and 2, the pilot relay 31 is provided with closing coils 41 and opening coils 42 which are energized from the spring opened relay 43 having a winding 44 which is connected in the distant control line 45. Resistances 46 and 47 are placed in the circuits leading to the coils 41 and 42 of the pilot relay 31 and serve to expedite or accelerate de-energization of the magnet coils 41 and 42, enabling the keying system to be operated at high speeds. Resistances 48 and 49 are line ballast devices arranged in the power circuit supplying the windings of the pilot magnets 41 and 42 and also assist in the reduction of the electrical inertia of the circuit.

Fig. 2 represents the arrangement for a

keying system in a high power transmitter installation wherein spares must be provided to enable quick transfer from one set of line relays or pilot relays to another set in case of breakdown without interrupting traffic. The duplicate line relays are represented at 44 and 44' with switch 50 for changing from one relay to the other. A switch 51 is provided to enable the transmitting circuits to be tested by means of local test key 52. A duplicate pilot relay 31' is provided with pilot magnets 41' and 42' and adapted to be connected in circuit by means of switch 53.

The keys 15 and 18 are supplied from a source which may be, for example, 500 volts. The pilot key 31 is supplied from a source which may be, for example, 120 volts. The determining factor in choosing voltage is the required inductance-resistance ratio of the circuit.

In the operation of the high speed signaling system the circuit at the control station may be closed automatically through an automatic transmitter, or otherwise, which sends the signal over the line wire 45 into the radio station operating the relay 44. When line wire 45 is energized armature 54 is contacted with contact 56 shunting the closing coil 41 and energizing the opening coil 42 of pilot relay 31. Armature 58 will contact with contact 57 and the closing coil 29 of key 18 and the opening coil 27 of key 15 is de-energized, thereby energizing the antennae system and enabling a signal to be transmitted. When the spring tensioned armature 54 is not attracted by the magnet coil 44 or, in other words, when the line wire 45 is not energized, the relay tongue 54 rests on contact 55 shunting the opening coil 42 and energizing the closing coil 41 of the pilot relay 31. Armature 58 then contacts with contact 59, thereby de-energizing opening coil 27 of key 18 and the closing coil 29 of key 15, thereby causing the absorbing resistance 14 to be electrically connected in the primary oscillating circuit and the secondary coupling coil 7 to be shunted, detuning the antennae system and preventing the transfer of energy from the primary oscillating circuit with inherent radiation.

As heretofore pointed out, I locate resistances in the various circuits and thereby accelerate keying to a considerable degree, enabling high speeds to be obtained and a large volume of traffic handled.

While I have described my invention in certain limited embodiments, it is to be understood that various modifications may be made, and that I intend no limitations upon the invention other than are imposed by the scope of the appended claims.

Having described my invention, I claim:

1. A high speed signaling system, com-

- prising a plurality of separate sets of keys, an armature for actuating each of said keys, a plurality of opening coils and a plurality of closing coils arranged to actuate each of 5 said armatures, a circuit including all of said coils in series, a resistance connected in said circuit, and means for energizing said coils, the energy being supplied to said coils by way of said resistance.
- 10 2. A high speed signaling system, comprising a plurality of separate sets of keys, each key in each set comprising a plurality of contacts and an armature arranged to open or close said contacts, a plurality of 15 opening and closing coils arranged to actuate said armature, and a circuit connection between said sets of keys including the closing coils of one set of keys and the opening coils of the other set of keys, means for 20 energizing said sets of keys, and a resistance connected between said energizing means and said coils whereby said contacts on one set of keys are open when said contacts on another set of keys are closed.
- 25 3. A high speed signaling system, comprising in combination a double set of keys, each set including a plurality of separate keys, and each key having a set of contacts, an armature, a plurality of opening coils 30 and a plurality of closing coils mounted adjacent said armature, and a pair of circuits connecting said sets of keys, each circuit including a resistance, and the closing coils of one set of keys and the opening coils of 35 the other set of keys connected in series whereby said circuits may be alternately energized and the contacts of one set of keys opened when the contacts of the other set of keys are closed.
- 40 4. A high speed signaling system, comprising in combination a pair of signaling keys, each including a plurality of sets of individual keys, a closing circuit and an opening circuit for each key, a circuit connection including said sets of keys comprising a series circuit having a resistance connected in series with the closing circuit of each of the keys of one set and the opening circuits of each of the keys of the other set 45 whereby said circuits may be energized causing the contacts of one set of keys to be opened when the contacts of the other set of keys are closed.
- 50 5. A high speed signaling system, comprising a plurality of separate sets of keys, an armature for actuating each of said keys, a plurality of opening coils and a plurality of closing coils arranged to actuate said armature, a circuit including all of said coils 55 in series, a resistance connected in said circuit, and means for energizing said coils, a control circuit, a pilot relay and a circuit connecting said pilot relay with said coils whereby energy is supplied to said coils by 60 way of said resistance, the closing coils of 65 one set of keys being de-energized while the opening coils of said set of keys are energized.
6. A high speed signaling system, comprising in combination a double set of keys, each set including a plurality of separate keys, and each key having a set of contacts, an armature, a plurality of opening coils and a plurality of closing coils mounted adjacent 70 said armature, and a pair of circuits connecting said sets of keys, each circuit including a resistance, the closing coils of one set of keys and the opening coils of the other set of keys connected in series, a control circuit, a line relay controlled by said circuit, a 75 pilot relay controlled by said line relay and connected with said double set of keys whereby said key circuits may be alternately energized and the contacts of one set of keys opened when the contacts of the other set 80 of keys are closed.
7. A high speed signaling system, comprising in combination a pair of signaling keys, each including a plurality of sets of individual keys, a closing circuit and an opening circuit for each key, a circuit connection including said sets of keys comprising a series arrangement having a resistance connected in series with the closing circuit of each of the keys of one set and the opening circuits of each of the keys of the other set, a control line, a line relay connected with said line, a pilot relay operated by said line relay, said pilot relay having a pair of contacts, one connecting with one of said signaling keys and the other connecting with said other signaling key whereby said sets of signaling keys may be independently energized causing the contacts of one set of keys to be 90 opened when the contacts of the other set of keys are closed.
- 95 8. A high speed signaling system, comprising a pair of separate sets of keys, each key in each set comprising a plurality of contacts and an armature arranged to open or close said contacts, a plurality of opening and closing coils arranged to actuate said armature, and a circuit connection between said sets of keys including the closing coils of one set of keys and the opening coils of the other set of keys, means for alternately energizing said sets of keys, a resistance connected between 100 said energizing means and each of said sets of keys, and means for alternately de-energizing said sets of keys whereby said contacts on one set of keys are open when said contacts on said other set of keys are closed.
- 105 9. A high speed signaling system, comprising means for generating sustained oscillations, a primary oscillating circuit connected with said means, a primary coupling coil connected in said circuit, a work circuit and a secondary coupling coil inductively connecting said work circuit with said primary 110 oscillating circuit, a plurality of keys shunt- 115

- 125
- 130

ing said secondary coupling coil, an artificial load circuit arranged to be connected with said primary oscillating circuit when said secondary coupling coil is shunted, a plurality of keys for shunting said artificial load circuit when said secondary coupling coil is not shunted, and series circuit connections including means for actuating said keys, resistances, and energizing means, whereby 10 said actuating means are energized through said resistances and de-energized in shunt with said resistances.

10. A high speed signaling system, comprising means for generating sustained oscillations, a primary oscillating circuit connected with said means, a primary coupling coil connected in said circuit, a work circuit

and a secondary coupling coil inductively connecting said work circuit with said primary oscillating circuit, an artificial load circuit, means for connecting said artificial load circuit in said primary oscillating circuit simultaneously with the operation of means for shunting said secondary coupling coil, said means comprising keys having a plurality of opening coils and a plurality of closing coils, the opening coils of said key in shunt with said secondary coupling coil being connected in series with the closing coils of said key in shunt with said artificial load, and resistances connected in series with said coils whereby said coils may be de-energized instantaneously. 20 25 30

HENRY E. HALLBORG.
